BRIDGE CONSTRUCTION

Ernest M. Wichert, Wilkinsburg, Pa., assignor to
The Wichert Continuous Bridge Corporation,
Pittsburgh, Pa., a corporation of Pennsylvania

Application June 15, 1934, Serial No. 730,757

10 Claims.

(Cl. 14—4)

This invention relates broadly to bridge construction, and more particularly to the construction of non-rigid continuous bridges. It relates still more particularly to the construction of bridges employing the now well known Wichert truss such as are described and claimed in my United States Reissue Letters Patent No. 18,973, reissued October 24, 1933. The present invention has to do primarily with methods of constructing or erecting non-rigid continuous bridges and structures useful in the erection of such bridges.

The invention will be described as applied to and embodied in the construction of bridges employing the Wichert truss. Such bridges may take a variety of specific forms, and only a few of such forms have been selected for the purpose of illustrating the present invention.

The Wichert bridge is a non-rigid continuous bridge having certain advantages described in my reissue patent above referred to, among which are the properties of being automatically adjustable and statically determinate. However, certain problems arise in the erection of such bridges, which are particularly acute where high intermediate spans are employed or where intermediate spans pass over deep water, highways, railroads, etc. Ordinary methods of construction would require that such spans be built substantially entirely on falsework, but the provision of falsework for intermediate spans under conditions such as those mentioned would be difficult or impossible in many cases and would at least unduly increase the cost of construction. However, as a non-rigid continuous bridge cannot be constructed as such by the cantilever method, the difficulties incident to economical erection have presented a serious problem.

My invention provides a method whereby non-rigid continuous bridges can be initially erected as rigid bridges and thereafter rendered non-rigid. This greatly simplifies the erection problem. For example, it makes it possible to erect intermediate spans without the use of falsework. The usual cantilever method may be employed, the bridgework being rendered rigid during erection and thereafter being rendered non-rigid.

For the purpose of rendering non-rigid continuous bridgework temporarily rigid during erection various means may be employed. For example, temporary erection members may be utilized and after erection has been completed such members may be either completely removed or adjusted so as to impart to the bridge the desired non-rigid continuous characteristics. One or

more such members may be used to render temporarily rigid the normally non-rigid quadrilateral of a Wichert truss over an intermediate pier or support.

Other details, objects and advantages of the invention will become apparent as the following description of certain present preferred embodiments thereof proceeds.

In the accompanying drawings I have shown, purely for the purpose of illustration, certain present preferred embodiments of the invention, in which

Figure 1 is a diagrammatic elevational view of a portion of a Wichert truss bridge showing the application of a horizontal erection member across the quadrilateral over an intermediate pier;

Figure 2 is a diagrammatic elevational view of a portion of a Wichert truss bridge showing the application of a vertical erection member across the quadrilateral over an intermediate pier, and also showing a modified type of support;

Figure 3 is a diagrammatic elevational view of a portion of a Wichert truss bridge showing the application of both horizontal and vertical erection members across the quadrilateral over an intermediate pier, and also showing a further modified type of support;

Figure 4 is a diagrammatic elevational view of a portion of a Wichert truss bridge of the tower type showing the application of a vertical erection member below the quadrilateral over an intermediate pier;

Figure 5 is a vertical transverse cross sectional view taken on the line V—V of Figure 4 and to enlarged scale;

Figure 6 is a diagrammatic elevational view of a portion of a Wichert truss bridge of the tower type showing the application of a horizontal erection member across the quadrilateral over an intermediate pier;

Figure 7 is a diagrammatic elevational view of a portion of a Wichert truss bridge of the tower type showing the application of a vertical erection member across the quadrilateral over an intermediate pier;

Figure 8 is a diagrammatic elevational view of a portion of a Wichert truss bridge of the tower type showing the application of both horizontal and vertical erection members across the quadrilateral over an intermediate pier;

Figure 9 is a diagrammatic elevational view of three spans of a Wichert truss bridge illustrat-

ing the use of horizontal erection members across the quadrilaterals over the intermediate piers;

Figure 10 is a diagrammatic elevational view similar to the left-hand side of Figure 9 illustrating the use of both horizontal and vertical erection members across the quadrilateral over an intermediate pier;

Figures 11 and 12 are diagrammatic elevational views similar to Figure 10 showing further modified constructions;

Figure 13 is a detail elevational view showing the construction and application of a horizontal erection member;

Figure 14 is a plan view of a portion of the construction shown in Figure 13;

Figure 15 is a vertical transverse cross-sectional view taken on the line XV—XV of Figure 13;

Figure 16 is a detail elevational view showing the construction and application of a vertical erection member;

Figure 17 is an elevational view, partly in vertical transverse cross section, of a portion of the construction shown in Figure 16;

Figure 18 is a detail elevational view showing the construction and application of horizontal and vertical erection members in combination;

Figure 19 is a detail elevational view showing the construction and application of a vertical erection member below the quadrilateral;

Figure 20 is a detail elevational view illustrating a further method of erection;

Figure 21 is a detail plan view of a portion of the construction shown in Figure 20;

Figures 22, 23, 24 and 25 are diagrams illustrating a method of erection;

Figures 26 and 27 are, respectively, detail elevational views of mechanism adapted for use in the method of erection illustrated in Figures 20 to 25, inclusive; and

Figure 28 is a horizontal cross-sectional view taken on the line XXVIII—XXVIII of Figure 27 and to enlarged scale.

Referring now more particularly to the drawings, Figure 1 illustrates diagrammatically a portion of a Wichert truss bridge mounted over an intermediate pier 30. A supporting member 31 is permanently and fixedly connected with the pier 30 and carries a pin 32 to which the lower members 33 of the quadrilateral are pivoted. Pivoted to each of the members 33 at its opposite extremity at 34 is one of the upper quadrilateral members 35. The upper quadrilateral members are pivoted together by a pin 36. Normally the quadrilateral made up of the two members 33 and the two members 35 is non-rigid. Such quadrilateral is, however, rendered temporarily rigid by the use of an erection member 37 joining the two pins 34. Such erection member transforms the bridgework into a rigid construction during erection and enables the use of the cantilever method to build out beyond the pier 30. The erection member 37 is preferably longitudinally adjustable so that when the opposite portions of the span have been constructed as cantilevers adjustment of the member 37, together with whatever slight longitudinal movement of one of the spans may be necessary, will enable connecting of the two halves of the span. After such connection has been effected the member 37 may be entirely removed, or it may be so adjusted as to impart to the bridgework non-rigid continuous characteristics. This may be done without removing the member 37 if it

is adjusted so as not to carry any load either in tension or in compression.

The construction shown in Figure 2 is similar to that of Figure 1 except that the erection member 38 extends vertically instead of horizontally as is the case with the erection member 37 of Figure 1. In each case, however, the erection member is adapted to withstand both tension and compression and thereby renders the quadrilateral temporarily rigid during erection. Figure 2 also illustrates a modified form of support, the supporting member 39 being mounted on the pier 40 for movement longitudinally of the bridge. Roller bearings are indicated diagrammatically at 41. Longitudinally movable supports will ordinarily be used over all piers but one to allow the bridge to take full advantage of its non-rigid continuous characteristics.

A similar construction is shown in Figure 3 except that in this figure two erection members 42 and 43 are provided. Each of the erection members 42 and 43 may be adapted to withstand tensile stresses only, in which case both members are necessary to render the quadrilateral temporarily rigid. In Figure 3 there is also shown a further modified form of support in which the supporting member 44 is permanently and fixedly connected with the pier 45. A link 46 pivoted to the supporting member 44 at 47 and to the lower members of the quadrilateral at 48 supports the structure but at the same time permits limited longitudinal movement thereof similarly to the supporting structure shown in Figure 2.

In Figure 4 there is illustrated a Wichert truss bridge of the tower type in which a supporting member 49 is permanently and fixedly connected with the pier 50. A tower member 51 is pivoted to the supporting member at 52 and is pivoted to the upper members of the quadrilateral at 53. Thus the quadrilateral is normally non-rigid. However, for erection purposes an erection member 54 is utilized which is connected with the lower members of the quadrilateral at 55 and with the pier at 56. As each of the members 51 and 54 is connected with the pier and with the quadrilateral, the quadrilateral is rendered rigid so long as the member 54 is effective.

Figure 5, being a transverse cross section through the construction of Figure 4, shows such construction as applied to both sides of the bridge. The construction above described for one side is duplicated on the opposite side.

Figure 6 also discloses a tower type Wichert truss bridge having a horizontally extending erection member 57 within the quadrilateral, and Figure 7 is similar but showing the use of a vertically extending erection member 58 within the quadrilateral. Figure 8 is likewise similar but discloses the use of two erection members 59 and 60 within the quadrilateral. Each of the members 59 and 60 may be adapted to withstand tension only, whereas each of the members 57 and 58 will normally be adapted to withstand both tension and compression.

In Figure 9 there are shown diagrammatically three spans of a Wichert truss bridge. The central span extends between piers 61 and 62 over each of which is a typical normally non-rigid quadrilateral. The bridge is anchored to the pier 61—that is to say, it is permanently and fixedly connected with such pier through the agency of a supporting member 63. Thus there is no longitudinal movement at the pier 61, such movement being provided for at each of the other piers. 75

The outer piers are shown at 64 and 65 and above each of these piers, as well as above the pier 62, is a link supporting member 66.

Each of the outer spans of the bridge is first 5 constructed in conventional manner upon the usual falsework 67. As each of the quadrilaterals overlying piers 61 and 62 is constructed there is inserted therein an adjustable erection member 68 capable of withstanding both tensile and compressive stresses. The respective erection members 68 render the quadrilaterals rigid during 10 erection so that the intermediate span may be constructed from opposite sides by the usual cantilever method and without the necessity of using 15 any falsework thereunder. During such construction the bridge is in effect and has the characteristics of a rigid bridge. When the construction has progressed to the point when connection of the opposite cantilever portions is ready to be 20 effected such portions can be raised and lowered by adjustment of the respective members 68. Likewise, the right-hand half of the bridge may be moved longitudinally by an adjustable tie member 69 so that the opposite halves of the 25 bridge may be brought into proper cooperative relationship in an extremely simple manner. After the opposite halves of the bridge have been joined at the center of the intermediate span the members 68 are either entirely removed or relieved of any stress, thereby transforming the 30 bridge into a non-rigid continuous bridge.

In Figure 10 there is shown a modified construction in which the quadrilateral is mounted upon a pier 70 by a link 71. The left-hand extremity of the outer span is mounted upon a pier 72 by a link 73. The outer span is constructed on falsework 74. Such span is maintained in fixed position by an adjustable tie member 75. The quadrilateral is rendered temporarily rigid during erection by erection members 76 and 77 each of which may be adapted to withstand tension only. The remainder of the bridge is constructed as above described in connection with Figure 9.

45 A further modification is shown in Figure 11. In this case the quadrilateral is mounted over a pier 78 by a link 79. The left-hand extremity of the outer span is mounted over a pier 80 by a link 81 and an adjustable tie member 82 is provided to fixedly position the span. No erection members are utilized within the quadrilateral in this construction, but an erection member 83 anchored to a temporary pedestal 83a fixedly connects one corner of the quadrilateral 50 with the ground. Such member 83 in combination with the tie member 82 insures rigidity of the quadrilateral during erection.

55 A further modification is shown in Figure 12. The quadrilateral is mounted over a pier 84 by a link 85. The left-hand extremity of the outer span is mounted over a pier 86 by a link 87 and an adjustable tie member 88 is provided. A predetermined weight 89 is suspended from the top pin of the quadrilateral, this having substantially 60 the same effect as the various provisions above described for maintaining the quadrilateral temporarily rigid. The same effect can be obtained by placing a flooring crosswise between the lateral pins of the quadrilateral and placing the weight 65 on such flooring.

70 Several specific constructions for performing the functions above described will now be explained. These specific constructions simply represent possible ways of effecting the desired 75 results and are purely illustrative.

In Figures 13, 14 and 15 there is shown in detail a horizontally extending erection member adapted to withstand both tension and compression and suitable for use in constructions such as those of Figures 1 and 6. In Figure 13 the 5 lower extremities of the upper members of the quadrilateral are shown at 90. Each of these is rigidly connected to a pair of matching gusset plates. In Figures 13 and 14 the pair of gusset plates to which the left-hand member 90 is connected is shown at 91a, 91b, and the pair of gusset plates to which the right-hand member 90 is connected is shown at 92a, 92b. The gusset plates 91a, 91b are connected through angles 94 to a thrust plate 95. A hydraulic jack 97 has its left-hand portion 96 bearing against the thrust plate 95 and its right-hand portion 105 bearing against another thrust plate 104 to be presently described.

The erection member is designated generally by 20 reference numeral 98. It comprises a pair of oppositely disposed channels 99 connected in spaced apart relationship with their flanges extending outwardly and adapted to receive the parts of gusset plates therebetween, as shown in 25 Figure 14. The erection member is shown as being bolted to the gusset plates 91a, 91b by bolts 100. Also passing through the gusset plates 91a, 91b and the erection member 98 is a relatively large bolt 101. The gusset plates are drilled to 30 snugly receive the bolt 101, but the channels 99 of the erection member are provided with elongated slots 102 to permit relative movement between the erection member and the bolt 101, as 35 will presently be described.

Connected with the respective channels 99 are angle members 103 and connected with the outwardly extending arms of such angle members is a thrust plate 104 against which the right-hand end 105 of the hydraulic jack 97 is adapted to 40 bear. The erection member is stiffened behind the angle members 103 by a cross plate 106 held in place by angle members 107. A plate 108 is connected with and extends across between the respective channels below the jack to serve as a 45 support for the jack when not in operative position. The right-hand extremity of the erection member 98 is pivotally connected to the gusset plates 92a, 92b by a bolt 109.

When the parts are in the position shown in 50 Figures 13 and 14 the erection member 98 acts either in tension or in compression between the respective pairs of gusset plates 91a, 91b and 92a, 92b and hence between the respective lateral pivots 110 and 111 of the quadrilateral. The erection member thus renders the quadrilateral rigid during erection, making it possible to erect the bridge by the cantilever method as above described. When the opposite halves of the span have been 55 constructed by the cantilever method and are ready to be connected together some adjustment of the erection member 98 will probably be desirable. The jack 97 is placed in operative position and pressure applied thereto so as to relieve the bolts 100 of substantial shearing stress. The bolts 100 are then removed and the nut on the bolt 101 is 60 somewhat loosened, whereupon the erection member is ready for longitudinal adjustment, which is effected by increasing or decreasing the pressure in the jack to extend or retract the same. After the ends of the span have been connected 65 together the pressure in the jack is relieved and the jack rendered inoperative. As the bolts 100 have been removed and the nuts on the bolt 101 have been loosened, the erection member 98 is 70 75

also rendered inoperative. Any relative movement between the erection member and the gusset plates 91a, 91b, either during the adjustment or upon rendering the erection member inoperative, is provided for within predeterminate limits by the elongated slots 102 in the erection member in which the bolt 101 slides. The erection member 98 may be either removed entirely or left in place but without taking any stress. In either event the bridge will assume non-rigid continuous characteristics.

The construction of the erection member 98 is such that during the adjustment such member will be under compression and not under tension. 15 The member is not designed to be adjustable under tension and will always be used in places where adjustment will be effected with the erection member under compression. As the horizontal erection member, when used alone, as in Figures 1 and 6, is always under compression during the adjustment the erection member 98 is used as such a horizontal erection member.

In Figures 16 and 17 there is shown a vertical erection member such as may be used in constructions of the type shown in Figures 2 and 7. In Figure 16 the pier is shown at 112 and is provided with a bearing plate 113 and an upwardly projecting pin 113a. A rocker 114 is mounted atop the bearing plate and is centered by the pin 113a which enters a cavity 115 in the rocker. The lower pivot pin 116 of the quadrilateral is carried by the rocker and the lower members 117 of the quadrilateral are pivotally connected by the pin 116. The upper members 118 of the quadrilateral are connected by the upper pivot pin 119 to which are also connected the upper members 120 of the adjacent spans. The erection member is designated by reference numeral 121 and comprises two sets of telescoping channels. The 30 upper channels 122 are connected with the pivot pin 119, and the lower channels 123 are connected with the pivot pin 116. The channels 122 telescope within the channels 123. Held by the inner channels 122 is a bolt 124 which passes through elongated slots 125 in the outer channels 123. Held by the outer channels 123 is a bolt 126 which passes through elongated slots 127 in the inner channels 122. Each of the bolts 124 and 126 is provided with nuts 124a.

50 A hydraulic jack 128 extends between and bears against the respective bolts 124 and 126. When it is desired to adjust the erection member 121, pressure is applied to the jack, thus enabling the erection member to be longitudinally adjusted as required. During adjustment the erection member is always under tension, and as the vertically extending erection member, when used as in Figures 2 and 7, is always subjected to tension during adjustment, the erection member 121 is used for this purpose. When it is desired to maintain the erection member 121 in a fixed adjusted position the respective channels 122 and 123 may be bolted together by bolts 129, as shown in Figure 16. The nuts 124a will normally be designed for the purpose only of maintaining the bolts 124 and 126 in place and will not ordinarily be relied upon to exert substantial friction on the channels 122 and 123.

In Figure 18 there is shown a construction such as would be suitable for use in the modifications of Figures 3 and 8. In Figure 18 the pier is shown at 130 and a rocker 131 is mounted thereon as in Figure 16. The rocker carries the lower pivot pin 132 to which the lower members 133 of the 75 quadrilateral are connected. The upper mem-

bers 134 of the quadrilateral are pivoted to the respective lower members 133 by pins 135 and to each other by the upper pivot pin 136.

In this modification two erection members 137 and 138 are utilized, each of such members simply comprising a pair of saddles having the opposite ends thereof connected by turnbuckles 139. Of course the erection members in this construction can withstand tension not only during adjustment but at all other times.

10 In Figure 19 there is shown a construction suitable for use in the form of Figures 4 and 5. The pier is shown at 140 and the tower at 141. The tower is pivoted at 142 to a supporting member 143 permanently and fixedly connected with the 15 pier. The upper members 144 of the quadrilateral are pivoted at 145 to the top of the tower 141. The lower members 146 of the quadrilateral are pivoted to the respective members 144 at 147 and are connected respectively with gusset 20 plates 148 which are pivoted together at 149. The quadrilateral is thus normally non-rigid.

An eye 150 is connected with the pier 140 at 25 151 and contains a pin 152. An erection member 153 connects the pin 149 and the pin 152. The erection member 153 comprises upper and lower eye members 154 and 155, respectively, each having a threaded shank and a turnbuckle 156 cooperating therewith. The erection member 153 may be relatively short and of substantial 30 cross-section so as to withstand either tension or compression at all times, both during adjustment and otherwise. However, the erection member 153 will normally be designed for tension only, and in such case blocks 153a cooperating 35 with wedges 153b resting on the pier 140 and underlying the respective gusset plates are used to sustain the weight of the bridgework during erection.

A somewhat different method of construction is 40 illustrated in Figures 20 to 28, inclusive. The method illustrated in such figures is for the construction of an over-water bridge in which the respective spans are separately constructed on barges and floated into place. Each span is 45 preferably constructed on a separate barge, the construction being effected in usual manner, such as on falsework. The quadrilaterals at the ends of the spans are maintained rigid during erection. A selected span is first set in place on its 50 piers. This may be either an end span or an intermediate span. It is preferably the anchored span, although another span may be utilized if desired and temporarily anchored.

The initial span above referred to has adjustable vertical erection members over the supports at both ends and has both of the inner members of each quadrilateral in place. The outer lower quadrilateral member at each end is also held in place, as will presently be described, but the 60 outer upper quadrilateral members are omitted, these later being set in place upon connection of the initial span with adjacent spans.

The erection of a bridge by this method is shown diagrammatically in Figures 22, 23, 24 and 65 25. In Figure 22 there is shown an initial span 157 mounted upon piers designated diagrammatically at 158. The inner quadrilateral members 159 are in place and at each end an adjustable vertical erection member 160 is provided. 70 The lower outer quadrilateral members 161 are held loosely in place and the upper and outer quadrilateral members, whose position will ultimately be as indicated by the dotted lines 162, are missing. Male guide members 163 are pro- 75

vided at the opposite ends of the span 157 above the respective erection members 160 to assist in positioning the adjacent spans in place.

Referring now to Figure 23, a span 164 is separately constructed on a barge with an erection member 165 in place in one end thereof, which end is in all respects similar to the left-hand end of the span 157 above described. The right-hand end of the span 164, however, has only the member 166 for closing the quadrilateral at the left-hand end of the span 157 and adapted to assume the position indicated by the dotted line 162. The span 164 is floated out into position on its barge and is moved laterally into place in end to end relationship with the span 157. At the right-hand extremity of the span 164 is a female guide member 167 adapted to receive the male guide member 168 to assist in properly positioning the two spans. Likewise the erection member 160 at the left-hand end of the span 157 is longitudinally adjustable and may be operated as necessary to enable the two spans to be connected. The member 166 is connected into the quadrilateral, after which the erection member 160 at the junction of the two connected spans may be removed or rendered inoperative. Another span 168 may be connected with the right-hand extremity of the span 157 as indicated in Figure 23. In Figure 24 the spans 164, 157 and 168 are shown as being completed except for the outer extremities of the spans 164 and 168 and removal of the guide members. Figure 25 shows the spans 164, 157 and 168 entirely completed and the guide members removed and additional spans being added.

The temporary erection members must remain in place in the outer or unfinished ends of the spans until other spans are connected therewith. However, as soon as a new span is added to the 40 existing structure the erection member at the junction may be dispensed with. Thus a non-rigid continuous bridge may be constructed by the flotation method by rendering the respective spans rigid during erection and thereafter transforming the construction into a non-rigid continuous bridge.

In Figure 20 the connection of two spans by the method just described is illustrated. It may be assumed that the left-hand span, viewing Figure 20, is in place and the right-hand span is being connected therewith. The erection member 169 is in place and the outer lower quadrilateral member 170 is loosely connected with the lower pivot pin 171 and is held up by a cable 55 172. The right-hand span is then moved into place. This is assisted by the guide device 175, as above explained. During movement of the right-hand span into place the stringer 176 is temporarily held up by a hanger 177 to allow the same to drop into place in proper cooperative relationship with the corresponding stringer after the right-hand span is in place. When the guide device 175 has brought the holes for the pin 174 into alignment such pin is inserted. The erection member 169 is then adjusted as necessary to enable the pin 173 to be inserted in the holes provided in the members connected thereby. The erection member 169 may then be rendered inoperative or removed, thus imparting to the bridgework the desired non-rigid continuous characteristics.

In Figures 26, 27 and 28 there is shown in detail a construction suitable for the erection member indicated in Figure 20. A rocker is shown at 75 178, such rocker carrying a lower pivot pin 179

to which are pivoted the lower quadrilateral members 180. Other portions of the construction clearly shown in Figure 20 are omitted in Figures 26 and 27. The adjustable erection member shown in Figures 26 and 27 is designated generally by reference numeral 181. It comprises telescoping members made up of channels, the lower of such members comprising the channels 182 and the upper thereof comprising the channels 183. The upper member telescopes within 10 the lower member. H-beams 184 are provided outside the channels 182 to stiffen the structure. Thrust plates 185 and 186 are connected, respectively, with the channels 182 and 183. This connection may be effected in any appropriate manner as, for example, by the method shown in Figure 15. A jack, illustrated purely diagrammatically at 187, bears between the thrust plates 185 and 186 to raise and lower the upper portion of the erection member. Strengthening members 188 are connected with the channels 183 and supports 189 are adapted to be interposed between the members 188 and the tops of the H-beams 184 to maintain the erection member in desired adjusted position. Bolts 190 passing through 20 portions of the members 188 and through the spacers 189 and also connected with the upper portions of the H-beams 184 may also be used so that the erection member 181 will withstand both tensile and compressive stresses when in 30 adjusted position. The erection member 181 is adjustable under compression.

While I have shown and described certain present preferred embodiments of the invention, it is to be distinctly understood that the same 35 is not limited thereto but may be otherwise variously embodied and practiced within the scope of the following claims.

I claim:

1. In the construction of a non-rigid continuous 40 bridge having adjacent spans connected and supported through a quadrilateral whose members are relatively movable, the steps consisting in forming the quadrilateral and maintaining it rigid until the essential members forming the 45 spans on opposite sides thereof are in place, and thereafter freeing the quadrilateral so that its members may move relatively to one another.

2. In the construction of a non-rigid continuous 50 bridge having adjacent spans connected and supported through a quadrilateral whose members are relatively movable, the steps consisting in erecting a portion of the bridge to one side of the quadrilateral and temporarily supporting such portion along its length, forming the quadrilateral, rendering the quadrilateral temporarily 55 rigid, erecting a portion of the structure on the other side of the quadrilateral, and thereafter freeing the quadrilateral so that its members may move relatively to one another.

3. In the construction of a non-rigid continuous 60 bridge having adjacent spans connected and supported through a quadrilateral whose members are relatively movable, the steps consisting in forming the quadrilateral and maintaining it 65 rigid by exerting a force across the panel formed by the members of the quadrilateral until the essential members forming the spans on opposite sides thereof are in place, and thereafter freeing the quadrilateral so that its members 70 may move relatively to one another.

4. In the construction of a non-rigid continuous 75 bridge having adjacent spans connected and supported through a quadrilateral whose members are relatively movable, the steps consisting

in forming the quadrilateral and maintaining it rigid by means extending across the panel formed by the members of the quadrilateral until the essential members forming the spans on opposite sides thereof are in place, and thereafter freeing the quadrilateral so that its members may move relatively to one another.

5. In the construction of a non-rigid continuous bridge having adjacent spans connected and supported through a quadrilateral whose members are relatively movable, the steps consisting in erecting a portion of the bridge to one side of the quadrilateral, forming the quadrilateral, rendering the quadrilateral temporarily rigid by exerting a force across the panel formed by the members of the quadrilateral, erecting a portion of the structure on the other side of the quadrilateral, and thereafter freeing the quadrilateral so that its members may move relatively to one another.

6. In the construction of a non-rigid continuous bridge having adjacent spans connected and supported through a quadrilateral whose members are relatively movable, the steps consisting in erecting a portion of the bridge to one side of the quadrilateral, forming the quadrilateral, rendering the quadrilateral temporarily rigid by means extending across the panel formed by the members of the quadrilateral, erecting a portion of the structure on the other side of the quadrilateral, and thereafter freeing the quadrilateral so that its members may move relatively to one another.

7. In the construction of a non-rigid continuous bridge having adjacent spans connected and supported through a quadrilateral whose members are relatively movable, the steps consisting in erecting a portion of the bridge to one side of the quadrilateral, forming the quadrilateral, rendering the quadrilateral temporarily rigid, erecting by the cantilever method a portion of the structure on the other side of the quadrilateral, and after the essential members forming said spans are in place freeing the quadrilateral so that its members may move relatively to one another.

8. In the construction of a non-rigid continuous bridge having adjacent spans connected and supported through a quadrilateral whose members are relatively movable, the steps consisting in erecting a portion of the bridge to one side of the quadrilateral, forming the quadrilateral, rendering the quadrilateral temporarily rigid, 5

erecting by the cantilever method a portion of the structure on the other side of the quadrilateral, adjusting the quadrilateral to bring said portion of the structure into proper position, and after the essential members forming said spans are in place freeing the quadrilateral so that its members may move relatively to one another.

9. In the construction of a non-rigid continuous bridge having adjacent spans connected and supported through a quadrilateral whose members are relatively movable, the steps consisting in erecting a span including two adjacent members of said quadrilateral, separately erecting another span including another portion of said quadrilateral, connecting said spans together and thereby completing said quadrilateral, during said connection maintaining said two members relatively rigid, and thereafter freeing said quadrilateral so that its members may move relatively to one another.

10. In the construction of a non-rigid continuous bridge having adjacent spans connected and supported through a quadrilateral whose members are relatively movable, the steps consisting in erecting a span including two adjacent members of said quadrilateral, maintaining said two members temporarily in adjustably rigid relationship, separately erecting another span including another portion of said quadrilateral, relatively adjusting said two members as necessary to permit connection of said spans and completion of said quadrilateral, connecting said spans together and forming said quadrilateral by connecting its several members together, and thereafter freeing said quadrilateral so that its members may move relatively to one another.

ERNEST M. WICHERT.
